ARTHUR H. POLLEN, OF LONDON, AND HAROLD ISHERWOOD, OF YORK, ENGLAND.

ELECTRIC FIRE CONTROL FOR GUNS.

1,314,208.

Specification of Letters Patent. Patented Aug. 26, 1919.

Application filed April 3, 1919. Serial No. 287,328.

To all whom it may concern:

Be it known that we, ARTHUR HUNGERFORD POLLEN and HAROLD ISHERWOOD, subjects of the King of Great Britain, residing at 14

5 Buckingham street, Strand, London, W. C., and Bishophill House, York, Yorkshire, respectively, have invented certain new and useful Improvements in Electric Fire Controls for Guns, of which the following is a

10 specification.

This invention consists in means for operating the receiver at the gun of the type known as the "follow the pointer receiver" in a particular way, namely, by setting on

15 the transmitter the rate of change of range.

Thus if it is known that the range for example is increasing at the rate of 500 yards a minute, the rate of change is set up on a dial at the transmitting end and the "follow 20 the pointer receiver" will, according to this invention, be caused to change its indications at this rate.

There is no particular novelty in the general problem of setting a receiver to operate 25 at a particular rate of change of range, and several mechanisms have been described by ourselves and others operating on this principle, as far as we are aware however, the principle has not been applied to the particular instrument known as "follow the 30 pointer receiver."

Special means are required for the application of the principle to this particular instrument owing to the fact that its scale 35 of ranges may not be uniform, but may have wider graduations at short ranges than at long ones, or may have wider graduations at the long ranges than at the short ranges depending upon the mechanism between the 40 dial and the sight itself.

In the accompanying drawings:

Figure 1 is a plan view partly in section of a mechanism embodying our invention.

Fig. 2 is a sectional elevation of a modified form of the same.

Fig. 3 is a diagrammatic view showing the "follow the pointer receiver" and the connections for operating it from the transmitting station.

50 Referring to the drawings:

The operative parts of our novel mechanism are mounted in and sustained by a suitable frame or casing A having a top B and covered by a suitable lid or cover C as

55 shown in Fig. 2.

Referring first to Figs. 1 and 3, 1 is an

insulated cylinder carrying contacts co-acting with the brushes 3 which are electrically connected with the receiver motor E at the receiving station by a cable 4 the electrical connections D, D', D² and D³ being such that by the rotation of the cylinder, the armature E' of the motor E will be rotated step by step, and by suitable gearing F will impart a like motion to the pointer G of a "follow the pointer receiver" as shown in . Fig. 3, which pointer is adapted to be read in connection with graduations on a scale H similar to the scale 6 before alluded to. The cylinder 1 is mounted on a shaft 7 journaled in bearings on the casing A which shaft is manually rotated by the handle 2 at the requisite speed, which speed is determined in the manner hereafter described. The rotations of the shaft 7 represent range and 75 are indicated by means of a pointer 5 traveling over a range scale 6 sustained by the top B of the casing, the pointer being carried by a vertical shaft 9^a journaled in a bearing 9^b sustained by the top of the casing. The shaft has a worm wheel 9^c fixed to it which meshes with a worm 9^d on the shaft 7. It will be observed that the scale (which corresponds to the scale of the well known "follow the pointer receiver") is far more 80 open at short ranges than at long ranges. In order that the operator may know at what rate the handle ought to be turned in order to impress on the "follow the pointer receiver" the definite rate of change of range 85 desired we provide a well known device consisting of a friction driven variable speed mechanism comprising the driving roller 8 splined to the shaft 7 which roller engages and frictionally drives the disk 10 with a 90 variable speed ratio depending upon the distance of the roller 8 from the center of the disk 10. The disk 10 is carried by a vertical shaft 10^a rotatably mounted in a bearing in the top B of the casing, which shaft carries 95 a pinion 34 engaging a gear wheel 35 mounted in a bearing on the casing top. The gear 35 engages a pinion 36 fixed to the lower end of a stem 37 mounted in a bracket bearing 38 sustained by the casing top, a housing 37^x being fixed to the upper end of the stem and giving support to a watch 12, the face of which is exposed to view through a hole in the lid C of the casing. The watch is provided 100 with a center second hand which rotates clockwise once a minute and the operator is instructed to turn the handle at such rate that

this motion of the second hand is reduced to zero, that is, he always turns the handle at such a speed that the watch itself is rotated counter-clockwise once a minute. This is facilitated by means of a line 18 engraved on the glass which covers the hole in the lid, the said line intersecting the axis of the second hand of the watch. By these means the disk 10 is always driven at a constant speed 5 and the shaft 7 is rotated by the operator at the required variable speed. The position of the roller 8 on the disk 10 is determined by setting the pointer 15 which indicates against the rate-of-change-of-range scale 14 10 to a certain rate of change of range. The pointer 15 is carried by a shaft 15^a mounted in a bearing on the lid C and has a pinion 16 fixed to its lower end which engages rack teeth on a slide 17 mounted to move in a 15 guide 18 sustained by the casing top. A link 19, provided with two longitudinal slots 19^a and 19^b, is pivoted at one end as at 19^a to the slide 17 and is fulcrumed between its ends on a pivot stud 20 extending through 20 the slot 19^b. This link is pivoted at its opposite end to a slide 9 by means of a pivot pin 9^c extending through the slot 19^b and carried by the slide 9. The slide 9 is provided with an arm 9^d which is forked at its 25 end and engages on opposite sides on the roller 8 on the shaft 7. As a result of the construction and operation of the parts above described, when the pointer 15 is set by means of a knurled head 40, with reference to the graduations on the scale 14, the slide 17 will be shifted, the link 19 swung about its pivot 20, and the slide 9 shifted, thereby setting the roller 8 at a given definite 30 distance from the axis of the disk 10. 40 We do not claim any novelty in the mechanism so far described, which however would only operate correctly on a receiver whose range graduations were equal at all parts of the scale. 45 We now proceed to describe the improvements which have been made by us for adapting the mechanism already described to operate with the unequal scale of the "follow the pointer receiver" shown in Fig. 3. 50 To this end we provide means for shifting the pivot 20 about which the link 19 rocks so as to give a faster angular speed to the receiver at short range than it has at long ones. This is done by means of a screw cam 55 groove 23 cut in a cam cylinder 24 which cylinder is rotatably mounted on center bearings sustained by the top B of the casing and is geared to the shaft 7 by the worm gear 24^a shown in Fig. 1. The pivot stud 60 20 before alluded to, is carried by a slide 21 mounted to move in a guiding slot in a bar 21^a sustained by the top B of the casing, and a pin 22 depends from the end of said slide and engages with the groove 23 of the cam 65 cylinder and shifts the pivot 20 laterally in

accordance with the part of the scale on which the transmitter and receiver are operating. Thus by this means it is possible to cause the "follow the pointer receiver" to be moved at a speed which will enable it to indicate correctly at the required rates of change of range, in spite of the fact that its graduations are unequal at different parts of the scale. 70

Referring now to Fig. 2 which shows a modified form of the mechanism to permit of the mechanism being driven by an electric motor, instead of driving the shaft 7 as above described we prefer in this case to drive the variable speed disk 10 from the motor M through the worm gears 30 and 31, shaft 32 and spur gears 33 and 34. The shaft 7 is then driven from the variable speed mechanism at a suitable rate by manually controlling the speed of the motor M so that the second hand of the watch is reduced to rest. This control is effected by cutting in and out resistance on the coil 25 by means of a slide contact I shown in Fig. 2. All that is necessary with this form of the mechanism is to set up the required rate of change of range on the dial 14 by means of the knurled head 40 and to continually adjust the slide contact so as to maintain the second hand of the watch 12 in coincidence with the 95 line 18 engraved on the glass above it. 90

What we claim is:—

1. In electrical fire control apparatus for guns of the kind in which motion is transmitted to a pointer at a receiving station 100 by means of a rotary shaft at a certain speed determined by an indicator at the transmitting end and, in which the speed of rotation transmitted is governed by the position of a roller in a roller-and-disk variable speed gear, the position of the roller being determined according to the indication of the aforesaid indicator, means for varying the speed of rotation transmitted to compensate for variations in the 105 scale readings of a scale which does not follow a straight line law, consisting in mechanism for transmitting motion to the roller from the indicator, in which mechanism the indicator rocks one end of a link about 110 a movable pivot engaging in a slot in the link the other end of the link being connected to the roller, the position of the pivot being determined by a suitably constructed cam driven from the shaft on which 115 the roller is mounted, so that the velocity transmitted is varied according to the position of the pivot, that is, according to the part of the scale on which the indication on the scale is being made. 120

2. In a mechanism of the type described, the combination of a movable transmitter pointer, a rotary shaft for moving the pointer, a variable speed gear coöoperating with the shaft and including a rotary disk 130

- and a wheel movable with the shaft and in frictional engagement with the disk and movable bodily radially of the disk, an indicator movable to indicate the rate of change 5 of range, a member operatively connecting the indicator with the wheel and acting, when the indicator is moved, to move the wheel radially of the disk, a "follow the pointer receiver" comprising a movable receiver pointer and an associated scale which does not follow a straight line law, means whereby said receiver pointer is moved by 10 the shaft, a rotary device operated by the shaft, and connections between said rotary device and the fulcrum of the link to move said fulcrum relatively to the link longitudinally thereof; whereby the velocity 15 transmitted by the shaft will be automatically varied in order to compensate in the movements of the receiver pointer for the variations in the scale of the "follow the pointer receiver." 50
- 20 3. In a mechanism of the type described, the combination of a movable transmitter pointer, a rotary shaft for moving the pointer, a variable speed gear coöperating with the shaft and including a rotary disk 25 and a wheel splined to the shaft and in frictional engagement with the disk and movable on the shaft radially of the disk, an indicator movable to indicate the rate of change of range, a link operatively connected at one 30 end with the indicator to be moved thereby, a movable fulcrum pin on which the link is fulcrumed between its ends, a slide connected with the opposite end of the link and engaging the wheel to move the same radially of the disk, when the link is swung on its 35 fulcrum by the indicator, a "follow the pointer receiver" comprising a movable receiver pointer and an associated scale which does not follow a straight line law, means whereby said receiver pointer is moved by 40 the shaft, a rotary device operated by the shaft, and connections between said rotary device and the fulcrum of the link to move said fulcrum relatively to the link longitudinally thereof; whereby the velocity 45 transmitted by the shaft will be automatically varied in order to compensate in the movements of the receiver pointer for the variations in the scale of the "follow the pointer receiver." 55
- 20 3. In a mechanism of the type described, the combination of a movable transmitter pointer, a rotary shaft for moving the pointer, a variable speed gear coöperating with the shaft and including a rotary disk 25 and a wheel splined to the shaft and in frictional engagement with the disk and movable on the shaft radially of the disk, an indicator movable to indicate the rate of change of range, a link operatively connected at one 30 end with the indicator to be moved thereby, a movable fulcrum pin on which the link is fulcrumed between its ends, a slide connected with the opposite end of the link and engaging the wheel to move the same radially of the disk, when the link is swung on its 35 fulcrum by the indicator, a "follow the pointer receiver" comprising a movable receiver pointer and an associated scale which does not follow a straight line law, means whereby said receiver pointer is moved by 40 the shaft, a rotary device operated by the shaft, and connections between said rotary device and the fulcrum of the link to move said fulcrum relatively to the link longitudinally thereof; whereby the velocity 45 transmitted by the shaft will be automatically varied in order to compensate in the movements of the receiver pointer for the variations in the scale of the "follow the pointer receiver." 50
- 20 3. In a mechanism of the type described, the combination of a movable transmitter pointer, a rotary shaft for moving the pointer, a variable speed gear coöperating with the shaft and including a rotary disk 25 and a wheel splined to the shaft and in frictional engagement with the disk and movable on the shaft radially of the disk, an indicator movable to indicate the rate of change of range, a link operatively connected at one 30 end with the indicator to be moved thereby, a movable fulcrum pin on which the link is fulcrumed between its ends, a slide connected with the opposite end of the link and engaging the wheel to move the same radially of the disk, when the link is swung on its 35 fulcrum by the indicator, a "follow the pointer receiver" comprising a movable receiver pointer and an associated scale which does not follow a straight line law, means whereby said receiver pointer is moved by 40 the shaft, a rotary device operated by the shaft, and connections between said rotary device and the fulcrum of the link to move said fulcrum relatively to the link longitudinally thereof; whereby the velocity 45 transmitted by the shaft will be automatically varied in order to compensate in the movements of the receiver pointer for the variations in the scale of the "follow the pointer receiver." 50

In testimony whereof we have hereunto set our hands in presence of the subscribing witnesses.
